UNITED STATES PATENT OFFICE.

GEORG GRABE, OF NIKOLASSEE, NEAR BERLIN, GERMANY, ASSIGNOR TO SIEMENS & HALSKE A.-G., OF SIEMENSSTADT, NEAR BERLIN, GERMANY, A CORPORATION OF GERMANY.

ELECTROMAGNETIC RELAY.

1,274,874.

Specification of Letters Patent. Patented Aug. 6, 1918.

Application filed December 27, 1915. Serial No. 68,870.

To all whom it may concern:

Be it known that I, GEORG GRABE, a citizen of the German Empire, residing at Nikolassee, near Berlin, Germany, have invented certain new and useful Improvements in Electromagnetic Relays, of which the following is a specification, reference being had therein to the accompanying drawings.

- 10 The invention relates to the type of electromagnetic relays, the armature and sets of contact springs of which extend parallel to the core and have their movable ends arranged at the same end of the relay.
- 15 The object of my invention is the provision of such a relay, which is cheap to manufacture and durable in use and has an advantageous course of the lines of force in order to avoid leakage of the magnetic flow.
- 20 Further objects of my invention are the improved arrangement of the contact springs and the armature, so as to have an easy access to the movable ends of same. Such a relay is capable of especially advan-
- 25 tageous use in connection with telephone exchanges. For obtaining a favorable course of the lines of force and therewith a great efficiency of the relay, the pole pieces are welded with a large base on the ends of the
- 30 side surface or on the front surfaces of the core and their breadth is successively increasing from the breadth on the core to that of the armature. Further the armature is arranged between the contact springs and
- 35 the winding of the core and moves upon energization of the magnet toward the core, so that its attraction is assisted by the leakage field of the magnetic flow of the lines of force. The seat of the armature at its
- 40 rear end is further so arranged, that the armature abuts in its operative position with a large surface upon a plate attached to the rear pole piece, so that the flow of the lines of force has not to overcome a
- 45 great resistance when flowing from the pole piece to the armature.

In order to have a free access to the movable ends of the contact springs and of the armature, when the relay is inserted in position, the motion of the armature is transmitted to the contact springs by means of intermediate studs abutting the contact springs at points behind the contacts.

In the drawings: Figure 1 is a side view

of a relay constructed in accordance with my invention and Fig. 2 is a front end view of the same. In these figures the make and break devices have been omitted for more clearness. Fig. 3 is a top view of a complete relay with four sets of contact springs. Fig. 4 is a side view, and Fig. 5 is a front end view of the same. In Fig. 5 two sets of springs have been omitted for more clearness.

In the embodiment shown in Figs. 1 and 2, the core *a* has a flat cross section and is arranged with its large side surfaces parallel to the flat armature *b*. The core is surrounded by the winding *c* and supports the pole pieces *d* and *e*, which are welded on the end parts of the upper large side surface of the core. The pole pieces extend upwardly and their breadth is successively increasing from that of the core to that of the armature. The front pole piece extends somewhat beyond the core so as to form a shoulder serving as a stop for a yoke attached to the free front end of the armature.

Instead of welding the pole pieces on the broad side surface of the core, they might also be welded on the narrow side surfaces of the same, which latter surfaces would then extend parallel to the armature. The arrangement shown in the drawings is however to be preferred, inasmuch as by it the distance between the axes of the armature and the core is shortened.

In the embodiment of the invention according to Figs. 3 to 5 the core *a*, the armature *b*, the winding *c* and the pole pieces *d* and *e* are arranged in the same manner as shown in Figs. 1 and 2.

To the pole piece *d* is fixed a plate *g* of magnetic material, for instance sheet iron, serving as a support for the armature and the make and break devices, consisting of four sets *k₁*, *k₂*, *k₃*, *k₄* of contact springs, which comprise each three springs *l₁*, *l₂*, *l₃*. The armature *b* is connected to the plate *g* by means of a blade spring *b'*, arranged between the plate *g* and the sets of contact springs. The arrangement is such that the armature when attracted abuts with its large upper side surface upon the lower side surface of the plate *g*. By this arrangement it is possible to adjust the contact springs before they are fixed to the relay and further an easy passage of the lines of force from

the pole piece *d* and the plate *g* to the armature *b* is obtained. To the free end of the armature *b* is attached a piece *h*, *i* of non-magnetic material, for instance brass, and 5 shaped as shown. The arc shaped part *h* extends beneath the protruding shoulder of the pole piece *e* and the part *i* consists of two clip shaped members, which are arranged between the sets of contact springs 10 and rest with their upper ends on lateral extensions *s* of the middle springs *l*₂ of the several sets.

When the relay is energized, the armature moves downwardly and this motion is assisted by the magnetic stray lines emerging 15 within the extent of the winding.

The armature moves by the intermedium of the parts *i* the middle contact springs *l*₂ also downwardly, whereby the contact with 20 the upper springs *l*₁ is broken and the contact with the springs *l*₃ is made. When the relay is deenergized the final position of the armature and of the contact springs is determined by the member *h* abutting the 25 shoulder of the pole piece *e*.

Between the sets of contact springs *k*₁, *k*₂ and *k*₃, *k*₄ are provided supports *n*, which are attached with one end by means of screws to the sets of contact springs and the pole 30 piece *d*, while they serve with their other end as a stop for lateral extensions *o* of the contact springs *l*₁, *l*₂. The supports *n* are provided with extensions *m*, which protrude 35 between the sets of contact springs and are shaped so that they may be gripped with a tool introduced from the front side of the relay for adjusting the supports *n*.

For adjusting the relay, the arc shaped piece *h* is at first bent for changing the 40 stroke of the armature and adjusting the contact springs by means of the abutting pieces *i*. The further adjustment of the set of contact springs is effectuated by bending the supports *n*. The extensions *o* of the 45 contact springs *l*₁ and *l*₂ are provided at such a distance from the free ends of the springs,

that the adjustment of the contacts may also be attained by bending the part of the springs between the extensions *o* and the contacts *q*. A further adjustment may be 50 obtained by bending the upper clip like members *i*.

I claim:

1. In an electromagnetic relay with a flat armature extending parallel to the core, the 55 combination of the armature arranged between the contact springs and the energizing winding on the coil, several sets of contact springs and adjustable means operating the contact springs and resting on lateral extensions of the springs.

2. In an electromagnetic relay with a flat armature extending parallel to the core, the combination of the armature provided between the contact springs and the energizing 60 winding on the coil, several sets of contact springs juxtaposed, adjustable means arranged between the sets of contact springs, which engage the contact springs and are secured to the armature and adjustable supports, which hold the upper and lower 65 springs of a set in their inoperative position.

3. In an electromagnetic relay with a flat armature extending parallel to the core, the combination of an armature provided between the contact springs and the energizing winding on the coil, and a blade spring clamped with one end between the rear pole 70 piece and a plate of magnetic material and attached with the other end to the armature 75 so that the latter, when attracted, bears with its upper broad surface on the portion of the blade spring connected to the magnetic plate.

In witness whereof, I hereunto subscribe 80 my name this 27th day of November A. D. 1915.

GEORG GRABE.
